[57] CLAIM

The ornamental design for hanger clip, substantially as shown and described.

DESCRIPTION

FIG. 1 is a left side, top and front perspective view of a hanger clip showing my new design;

FIG. 2 is a side elevational view thereof, the side opposite being identical;

FIG. 3 is a front elevational view thereof, the rear view being identical; and

FIGS. 4 and 5 are, respectively, top and bottom plan views thereof.

The broken line showing of hooks in FIG. 1 is for illustrative purposes only and forms no part of the claimed design.

FIG.1.

FIG.2.

FIG.3.

FIG.4.

FIG.5.
